LOOSE-LEAF BINDER CONSTRUCTION

John C. Condon and Otto Felix, Chicago, Ill., assignors to Sears, Roebuck and Co., Chicago, Ill., a corporation of New York

Application August 27, 1948, Serial No. 46,428

2 Claims. (Cl. 129—1)

1

This invention relates to improvements in bookbinding apparatus and is concerned more particularly with the construction of loose leaf binder rings which may be spring tensioned between open and closed positions so that perforated pages may be inserted and removed at will.

In the construction of loose leaf binder apparatus heretofore, the economic motive has dictated various practices in order to minimize the initial cost of production. Accordingly, assemblies have been so designed and integrated that upon the failure of any part due to wear or rupture, the entire apparatus was rendered unserviceable. The impracticability of field repair was most frequently indicated by the difficulty of disassembly as well as other factors which have made the entire ring binder discardable as scrap upon the rupture or failure of what frequently comprised only a minor part.

The present invention concerns itself primarily with a new mode of construction and interrelation of parts which will afford facile repair interchangeability and ready replacement, so that upon wear or failure of any of its various parts, replacement and repair may be made under field conditions at small cost, and with but pocket tool facilities.

A principal object of the present invention, therefore, is to afford a loose leaf ring binder construction which is simple and rugged in design and whose parts are interchangeable as to various sizes of binders so that they can be used for multiple rings of any number and so as to render field repair service facile and practical. The way in which these objects are achieved consists primarily in the provision of a metallic backing member to which are secured, in the proximity of each ring location, journal brackets through which a main operating rod extends longitudinally and passes through all of the journal brackets in which it is threaded through a relatively removable portion of each ring assembly so as to operate the several of them in unison. Spring tension means on the operating bar act in an overcentering manner, tensioning the assembly into both its open and closed positions. The backing member is pivoted throughout its entire length, on both sides, after the manner of piano hinge construction, to metallic cover elements of the binder and at its rear said backing member is provided with a doubled-over full length channel recess into which may be longitudinally slid markers or identification labels whereby the binder may be identified

2

when observed in an upright position such as during shelf storage array.

For a better understanding of the details of construction regarding this invention and the practices whereby its objects are achieved reference will now be had to the accompanying drawings and to the following detailed specification in which similar reference numerals designate corresponding parts throughout and in which:

Fig. 1 is a plan view of a binder assembly in spread open condition with a portion of one cover broken away, having incorporated therein various features of the present invention;

Fig. 2 is a sectional view longitudinally of the backing strip and operating rod and is taken approximately on line 2—2 of Fig. 1;

Fig. 3 is a fragmentary end elevational view of the backing strip with the cover elements disposed in closed position;

Fig. 4 is a fragmentary transverse sectional view taken approximately on line 4—4 of Fig. 1;

Fig. 5 is an enlarged fragmentary plan view of one end of the backing strip on which the detenting spring and operating arm are disposed; and

Fig. 6 is a transverse sectional view through a modified form of backing strip showing the binder rings equipped with spring pressed sheet protectors.

The general arrangement of the parts of this invention follow the conventional mode so that to a principal backing strip 11 formed with pintle encircling wings 12 and 13, there are secured at regular intervals as by riveting the U-shaped journal channels 14, 15 and 16, see particularly Fig. 2. The upstanding and parallel end portions 17 of each channel are provided with circular openings all disposed to register in longitudinal alignment so that there may be received therethrough the main shank 18 of the operating member having a perpendicularly disposed arm 19 at one end thereof.

While the channels 14, 15 and 16 might be welded or otherwise to the backing strip 11, it has been preferred to secure these elements by means of rivets 21, so that if, and when, it is desired to do so, they may be replaced at small trouble and cost by simply removing the old rivet heads, punching out the rivet stubs, and substituting new rivets that can be swaged over with field service riveting tools.

The backing strip 11, through its center portion, is flat and of predetermined width. At each side of the flat center portion, the strip is

doubled over as at 22 and reversed again as at 23, affording thereby cross-sectionally a recess throughout the length of the backing member into which there may be slid fibre or other pliable marker strips 24 faced with transparencies 25. In this way, different volumes made up of bookbinders according to the present teaching may be differentiated from one another under conditions of easy interchangeability, so that any bookbinder may be rendered serviceable to any class or identification of subject by the simple expedient of replacing its markers 24-25.

The shank or beam 18 is square in cross-section as best seen in Figs. 4 and 6, and may be constructed of a piece of square steel stock bent at one end to provide the operating handle 19, Fig. 2. Where it passes between the upstanding portions 17 of each channel member 14, 15 or 16, the shank 18 is threaded to a square tubular sleeve 26 of such length as to be rotatably confined between the upstanding portions 17.

This arrangement is best illustrated in Figs. 2, 4 and 5. Since each square tubular section 26 has welded to it the rotatable half 27 of a binder ring the stationary half 28 of which is secured to one of the channels 14, 15 or 16 as at 29, Fig. 4, it will be understood that when the beam 18 is rotated on its longitudinal axis, so too will all of the binder ring halves 27 be rotated to the dotted in position featured in Figs. 4 and 6.

The rotation of beam 18 is yieldably resisted by a detent spring 29, Fig. 5, which exerts an expansive force between the end bracket 31 integral with a longitudinal strip 32 secured to the backing member 11, and a thrust washer 33 whose travel is limited by the stop pin 34. The effect of the force exerted by spring 29 is to urge the beam 18 rightwardly as viewed in Figs. 2 and 5 compelling the detent projection 35 located near the bottom of the operating arm 19 to seek entry within a seating dimple in the bracket 31 with which it is in alignment when the ring elements 27 and 28 are closed as best indicated in Figs. 5 and 6. Another such dimple may be provided at 36 in the surface of bracket 31 in the arcuate path of such projection 35 and at a predetermined distance from the closed position of the ring elements so that under the same tension of spring 29 the ring elements 27 and 28 may be held ajar thereat.

The beam 18, being journaled throughout its length in the flanges 17 as well as in the end flanges 31 and 37 of the center strip 32 for limited rotational movement, is also held against inadvertent withdrawal by the aforescribed spring 29 together with its thrust washer 33 and tie pin 34. In order to disassemble these parts, therefore, it only becomes necessary to drive the thrust pin 34 out of its seat aperture in the body of beam 18, whereupon the latter member can be slid longitudinally out freeing all of the sleeves 26 for repair or replacement purposes. In this way is afforded facile disassembly and interchangeability which makes it possible to service ring binders in disrepair, as well as to alter the ring binder equipment whereby to increase or decrease the number of ring sets 27-28 at will.

The importance of being able to utilize the indicated range of interchangeability and field serviceability is particularly enhancing to a ring binder construction of de luxe qualities where the component parts may be reinstated into service notwithstanding the inevitability of wear that may be suffered. Thus it is to be observed

that in a ring binder such as that illustrated the retrievable qualities are particularly important. Attention is now directed to the extremities of the backing member 11 which are formed with the hinge pintles 12 and 13. These are hinge elements which cooperate with the pintles 41 and 42 of sheet metallic formed binder covers 43 and 44. Longitudinal hinge pins 45 extend through the respective alignments of pintles and make for rugged and secure hinge elements capable of undergoing severe and repeated rigors of wear. The peripheral edging of the cover elements 43 and 44 is preferably beaded as at 46 on the three outer edges of each cover. This quality of finishing imparts a rich appearance to the binder covers and provides the tubular housing into which there may be inserted the end plugs 47 which receive and confine the extremities of the hinge pins 45.

Center panel areas of each cover 43 and 44 may be reinforced against vibrational bowing or buckling by having formed therethrough X-embossments 49 of shallow circular cross-section. This not only imparts a high rigidity to the cover member but more significantly it endows it with a luxuriant quality of appearance and sturdiness while yet maintaining lightness of weight. The panel areas on the external sides of the covers 43 and 44 may be ornamented with covering material that may be inlaid within the beaded edging 46. Also these covers may be treated with a surfacing ornamentation such as flocking, enameling or lithographing.

Since wear will be limited to the movable ring elements, including portions 27 and the tubular sleeves 26 in accordance with the structural arrangement disclosed, replacement of these parts can be had at small cost and with but field servicing tools. Also it is to be noted that the universal qualities of these parts will afford a practice whereby with a small stock of replacement parts a repairman is able to service ring binders of various proportions utilizing different numbers of rings according to the size of binder.

In order to prevent the tearing out of sheets during opening and closing of the binder covers, there is illustrated in Fig. 6 an auxiliary apparatus for maintaining the sheets clear of the ring pivot mechanism. This apparatus includes a pair of pusher discs or washers 51 and 52 carried upon the binder rings 28 and 27 respectively. Compressible coil springs 54 maintain these washers well away from the axial proximity of the binder, and in order to better support the compression spring on element 28, a flange 55 may be welded near the anchor end of this member. On the ring 27, the compression spring 54 may be permitted to abut the side of the square tubing 26. In this way the sheets 53 are held clearer of the pivoting or beam mechanism where they might otherwise be torn or mutilated.

While the present invention has been explained and described with reference to a particularly contemplated embodiment, it will be understood that numerous modifications and variations may be made without departing from the essential spirit or scope thereof. Accordingly, it is not intended to be limited by the particular details illustrated in the accompanying drawings nor by the language in the foregoing specification except as indicated in the hereunto appended claims.

The invention claimed is:

1. In a ring binder, a backing member comprising a metallic channel with longitudinal

sides doubled over in opposite symmetry affording a central recess for receiving identification material slidable thereinto, a plurality of U-shaped journal supports secured to said member in end-to-end alignment and spaced one from another on the inner surface of said backing strip, binder ring elements associated with each of said U-shaped supports split into semi-circular halves with corresponding halves of said rings secured to said supports, polygonal tubular sections confined within said supports having secured thereto the other halves of said binder rings, an operating beam journaled in and extending through all of said supports and polygonally conforming with said tubular sections, and spring detent means for holding said operating beam in either its ring-closed or its ring-open positions.

2. In a ring binder construction, a main supporting member formed of a metallic channel whose sides are doubled over in reverse symmetry flanking a longitudinal recess which may serve for receiving marking material, a plurality of U-shaped brackets secured in end-to-end alignment on the inner surface of said member and spaced one from another longitudinally, polygonal tubular sections confined within said

5
10

brackets, severable binder ring elements associated with each of said brackets of which corresponding portions are secured to said brackets, and the remaining portions are secured to said tubular sections, a bar extending through all of said brackets and rotatively coupling said tubular sections, and spring means for detenting said bar in ring-open and ring-closed positions.
